CLAIM

The ornamental design for a milling machine, as shown and described.

DESCRIPTION

FIG. 1 is a perspective view of a milling machine, showing my new design.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof.

FIG. 8 is a perspective view thereof.

FIG. 9 is a perspective view of a second embodiment of a milling machine, showing my new design.

FIG. 10 is a front view of FIG. 9.

FIG. 11 is a rear view of FIG. 9.

FIG. 12 is a left side view of FIG. 9.

FIG. 13 is a right side view of FIG. 9.

FIG. 14 is a top plan view of FIG. 9; and,

FIG. 15 is a bottom plan view of FIG. 9.

The dotted lines form no part of the claimed design.
